UNITED STATES PATENT OFFICE.

RICHARD FITZ POWER, OF LONDON, ENGLAND, ASSIGNOR TO MORLAND & IMPEY LIMITED, OF BIRMINGHAM, ENGLAND.

LOOSE-LEAF-SECURING MECHANISM.

Application filed January 29, 1926, Serial No. 84,599, and in Great Britain May 25, 1925.

My invention relates to improvements in mechanically operated means of opening and closing the securing mechanism of loose leaf books, and the like, so that leaves can be removed and replaced, and the objects of my invention are:—

First: To provide means by which the binding mechanism which secures the loose leaves in book form can be effectively and very rapidly operated to release a leaf or to add a leaf to the bunch already in the binding mechanism, and

Second: To provide that this may be done by a substantially unskilled operator, though such binding mechanism is strong enough to hold the leaves with considerable force.

It should be mentioned that in my concurrent application for a patent of the United States filed on the 29th day of January, 1926, Serial No. 84,598, I have described both a sheet adapted for this particular purpose and an anchoring and binding mechanism for holding such sheets in bulk.

Fig. 1 is one form of the binding mechanism referred to in such concurrent application, the numbers on Fig. 1 being the same as those on the concurrent case, and it represents a simple form of such mechanism.

Fig. 2 is a perspective view showing a base frame adapted for use with a binder such as that shown in Fig. 1.

Fig. 3 is a sectional side elevation of a casing built on the base frame of Fig. 2.

Fig. 4 is a plan view of Fig. 3 with the operating handle moved thru 90°.

Fig. 5 is a plan view of a base plate with a modified form of mechanical operation adapted to deal with a plurality of binders at the same time.

Fig. 6 is a section on the line VI—VI of Fig. 5.

Fig. 1 shows a leaf such as 1 secured on anchoring bars 16, 17, a bunch of such leaves being intended to be secured between the covers 23 and 28, the bars being attached through the medium of binding plates 42, 43 to eyes 18, 19 respectively, and the eyes sliding on the spindle 20; this spindle 20 is supported by hinge pieces 21, 22 attached to the cover board 23, and riding on the spindle 20 between the eyes 18 and 19 is a helical spring 26 tending to press the eyes 18, 19 apart.

It will be seen that owing to the action of the spring 26 the bars 16, 17 are pressed

firmly into the corners 4, 5 of the recessed leaves 1, and thus hold them from being dislodged; when it is desired to remove a leaf or leaves the bars 16, 17 must be moved towards each other, being attached to the eyes 18, 19.

The anchoring bars 16, 17, in this case made double by the addition of the inner bars 14, 15, are made telescopic, spindles 34, 35, 36, 37 attached to binding plates 40, 41 being arranged to slide within the portions 14, 15, 16, 17 respectively, and springs 38, 39 being employed to draw binding plates 40, 41 always towards the binding plates 42, 43 respectively.

The hinged pieces 21, 22 which secure the spindle 20 to the cover board 23, form stops which limit the outward movement of the eyes 18, 19 actuated by the spring 26. A top cover board 28 is connected by other hinge pieces 44, 45 with the spindle 46 carrying another spring 27 and working in precisely the same way as the spring 26 by pressure against eyes carried by binding plates 40, 41.

The binding plates 40, 41 actuated by the springs 38, 39 thus clamp the sheets between themselves and the binding plates 42, 43, and hold them in place.

The means just described for binding together a bunch of loose leaves are not claimed herein as they are the subject-matter of claims in my copending application before mentioned.

An apparatus provided for operating a binding mechanism such as that shown in Fig. 1 is shown in Figs. 2, 3, and 4, and it consists in a base frame 50 to which is attached the casing 51, which may, if desired, be provided with spring guides 52 tending to direct the covers 23, 28 of the binder so that it drops into place correctly on the mechanism of the base frame 50.

The mechanism of the base frame is for the purpose of supporting a pair of abutment plates 54, 55 moving outwardly to separate the binding plates 40, 41 and 42, and 43, and a pair of abutment plates 56, 57 supported so as to move inwardly the telescopic bars 14, 15.

The plates 54, 55 are carried by guides 58, 59 working in bearings 60 and 61 of the base frame, and are arranged so that they push against the binding plates 40, 41, and 42, 43 so as to push out the inner members 110

34, 35 of the telescopic bars 14, 15, thus leaving the sheets loose on the co-operating anchoring bars 16, 17. These bars 16, 17 are shown contracted with the sheet loose in Fig. 4.

The operation of the abutment plates 56, 57 is achieved by connecting rods 66, 67 attached at one end to the disc 65, with 66 attached at its other end to the slide 64 and 10 67 attached at its other end to the slide 63, these slides working in bearings 62 on the base frame. The other pair of abutment plates 54, 55 are controlled by connecting rods 70, 71 connected as to one end to points 15 on the disc 65 intermediate of the rods 66, 67, and on the opposite side of the disc, and the disc 65 carried by the spindle 68 is turned by the lever 69 fixed thereon and provided with a space in the base frame 50 for swinging 20 through about half a circle. A feature of this swinging is that the pivot ends of the rods 70, 71 on the disc 65 are so arranged that in the extreme position of the lever handle 69 the pivot ends of the links pass 25 the dead centre of the disc 65 and are thus locked against movement in the opposite direction when the stress of holding the plates 54, 55 is left on the binding mechanism. The binding mechanism is thus held open 30 automatically while leaves are removed or replaced.

The same passing of the links 70, 71 past their dead centre on the disc 65 also serves to hold together the links 66, 67 which have 35 drawn together the abutment plates 56, 57, thus keeping the anchoring bars 16, 17 out of their locking corners in the sheet 1.

In practice a bunch of sheets such as 1 having been secured by the binding mechanism, can be treated as a book and used in 40 the ordinary way. When leaves are required to be removed or inserted, the book 23, 28 is simply dropped onto the base frame 50, the handle 69 pulled round from the position shown in Fig. 2 past the position shown 45 in Fig. 4 until it points in the opposite direction to that of Fig. 2, when the plates 54, 55 have pushed out the binding plates 40, 42 so as to release the sheets against the action of the springs 38, 39 and the plates 56, 57 have drawn in the anchoring bars 16, 17. The sheets are then quite loose and can 50 be dealt with as required, while a single return movement of the handle 69 immediately locks the whole together again as a book 55 which can be lifted from the casing 51.

Figs. 5 and 6 show a similar arrangement 60 of abutment plates but worked by toggle links 74, 75 pivoted to abutment plates 76, 77, and also to abutment plates 78, 79, which latter are connected by nuts to the spindle 80 running the full length of the base frame 81 and operating three sets of unbinding mechanisms.

The casings such as 82, 83, 84 are all con-

nected in similar fashion to that shown in Fig. 3 for the reception of binding cases which can all be operated at the same time, or only one of the compartments 81, 82, 83, 84 need be occupied, as desired. The spindle 70 75 is turned in its bearings by a handle 85, and the abutment plates will stay at any position in which they are left by this handle, so that the sheets can be removed as soon as they are loose on the anchoring devices. 75

What is claimed is:—

1. In a loose leaf securing system in which the leaves are secured by a binding mechanism having spring-controlled anchoring bars reciprocable against the spring action, 80 the combination of a base frame, a pair of abutment plates supported in the said base frame, and mechanical means adapted to reciprocate the said abutment plates when operated with the binding mechanism placed 85 on the said base frame, whereby to effect the movement of the anchoring bars and the release of leaves contained in the said binding mechanism.

2. In a loose leaf securing system, the 90 combination of a base frame adapted for use with a binding mechanism having anchoring bars and binding plates, a series of abutment plates supported in said base frame, means for reciprocating some of said 95 abutment plates longitudinally of said frame, and means for reciprocating others of the abutment plates transversely of the said frame, the two movements when the binding mechanism is placed on the frame 100 serving to cause corresponding movements of the anchoring bars and the binding plates respectively for the purpose of releasing the leaves held by said binding mechanism.

3. In a loose leaf securing system having 105 leaves secured by a binding mechanism, the combination of a base frame, a series of abutment plates supported in the said base frame, means for reciprocating some of the 110 said abutment plates longitudinally of the said frame, and means for reciprocating others of the said abutment plates transversely of the said frame, the two movements, when the binding mechanism is connected with the said base frame, serving to 115 release leaves held by the said binding mechanism.

4. In a loose leaf securing system in which the leaves are secured by a binding mechanism having spring-controlled anchoring 120 bars and spring-controlled binding plates, the said anchoring bars and the said binding plates being reciprocable respectively in directions at right angles to each other, the combination of a base frame, a pair of abutment plates and guides supporting same so as to be slidable longitudinally in the said base frame, a pair of abutment plates and guides slidable transversely of the said frame, a spindle disposed centrally of the 130

5 said base frame, means for connecting the said spindle with the said pairs of abutment plates respectively, and a handle connected with the said spindle, whereby turning of the handle ensures reciprocation of the said abutment plates in the directions desired.

10 5. In a loose leaf securing system in which the leaves are secured by a binding mechanism having spring-controlled anchoring bars and spring-controlled binding plates, the said anchoring bars and the said binding plates being reciprocable respectively in directions at right angles to each other, the combination of a base frame, a pair of abutment plates and guides supporting same so as to be slidable longitudinally in the said base frame, a pair of abutment plates and guides slidable transversely of the said frame, a spindle and disc disposed centrally 20 of the said base frame, links connecting the said disc with the said pairs of abutment plates respectively, and a handle adapted to turn the said spindle so as to operate the said abutment plates to reciprocate as required when the binding mechanism is placed in connection with the said abutment plates.

30 6. In a loose leaf securing system in which the leaves are secured by a binding mechanism having spring-controlled anchoring bars and spring-controlled binding plates, the said anchoring bars and the said binding plates being reciprocable respectively in directions at right angles to each other, the combination of a base frame, a pair of abutment plates and guides supporting same so as to be slidable longitudinally in the said base frame, a pair of abutment plates and guides slidable transversely of the said 35 frame, a spindle disposed centrally of the said base frame, a disc on the said spindle, links connecting a pair of the said guides with opposite sides of the said disc, and links connecting the other pair of the said 40 guides with intermediate opposite sides of the said disc, and a lever handle connected to the said spindle adapted to reciprocate the said abutment plates by a partial turn of the said spindle.

45 7. In a loose leaf securing system in which the leaves are secured by a binding mechanism with covers having spring-controlled anchoring bars and spring controlled binding plates, the said anchoring bars and the said binding plates being reciprocable respectively in directions at right angles to each other, the combination of a base frame, a pair of abutment plates and guides supporting same so as to be slidable longitudinally in the said base frame, a pair of abutment plates and guides slidable transversely of the said frame, a spindle disposed centrally of the said base frame, a disc on the said spindle, links connecting a pair of the said 50 guides with opposite sides of the said

disc, and links connecting the other pair of the said guides with intermediate opposite sides of the said disc, a lever handle connected to the said spindle, and a casing supported on the said base frame adapted to 70 guide the covers and the binding mechanism to locate the said anchoring bars and binding plates in correct relation with the said abutment plates so that operation thereof by the said handle opens the said binding mechanism. 75

8. Loose leaf securing mechanism comprising leaves having open-ended recesses with undercut ends in combination with telescopic anchoring bars disposed within the area 80 of such recesses, spindles disposed adjacent each end of the said anchoring bars at right angles thereto, binding plates attached to the said anchoring bars, those on one side to the outer telescopic members and those on 85 the other side to the inner telescopic members, eyes on the said binding plates slidable on said spindles, springs tending to draw the said binding plates together, helical springs on the said spindles disposed between the 90 said eyes to press them apart, cover members attached to the said spindles so as to form stops limiting the movement of the said anchoring bars, a base frame, a 95 pair of abutment plates and guides supporting same so as to be slidable longitudinally in the said frame, a pair of abutment plates and guides slidable transversely of the said frame, a spindle disposed centrally of the 100 said base frame, a disc on the said spindle, links connecting a pair of the said guides with opposite sides of the said disc, and links connecting the other pair of the said guides with intermediate sides of the said disc, and a lever handle connected to the said 105 spindle adapted to reciprocate the said abutment plates when associated with the said anchoring bars and binding plates respectively by a partial turning of the said spindle. 110

9. Loose leaf securing mechanism comprising leaves having open-ended recesses with undercut ends in combination with telescopic anchoring bars disposed within the area 115 of such recesses, spindles disposed adjacent each end of the said anchoring bars at right angles thereto, binding plates attached to the said anchoring bars, those on one side to the outer telescopic members, and those on the other side to the inner telescopic members, eyes on the said binding plates slidable on 120 said spindles, springs tending to draw the said binding plates together, helical springs on the said spindles disposed between the said eyes to press them apart, cover members attached to the said spindles so as to form stops limiting the movement of the said anchoring bars, a base frame, a pair of abutment plates and guides supporting same so as to be slidable longitudinally in the said 125 130

- base frame, a pair of abutment plates and guides slidable transversely of the said frame, a spindle disposed centrally of the said base frame, a disc on the said spindle, links connecting a pair of the said guides with opposite sides of the said disc, and links connecting the other pair of the said guides with intermediate opposite sides of the said disc, a lever handle connected to the said spindle, a casing supported on the base frame adapted to guide the covers of the binding mechanism to locate the said anchoring bars and binding plates in correct relation with the said abutment plates so that a partial turn of the said lever handle operates the said abutment plates to control the said anchoring bars and binding plates.
10. In a loose leaf securing apparatus, the combination of leaves having open-ended recesses with undercut ends, a pair of anchoring members located within the area of such recesses when a number of such leaves are massed together, cover boards, bars attached to said cover boards slidably carrying said members, springs disposed so as to cause said members normally to occupy said undercut ends and removable mechanically operated means including slidable abutment plates adapted to withdraw said anchoring members within the said recesses.
20. In a loose leaf securing apparatus the combination of leaves having open-ended recesses with undercut ends, a binding mechanism associated with a mass of the said loose leaves comprising a pair of anchoring members located between the undercut ends adjoining one such recess, pairs of binding plates, one pair in association with each anchoring member, tension springs connecting binding plates of a pair so as to cause them to compress the said leaves between them, and removable mechanically operated means embracing slidable abutment plates adapted to withdraw said anchoring members and expand said binding plates to release the said leaves.
30. In a loose leaf securing system, the combination of a base frame having two pairs of relatively movable abutment plates

reciprocably mounted in directions substantially at right angles to each other, thereby to release a leaf-binding and leaf-anchoring mechanism, and means for actuating both pairs of abutment plates simultaneously.

13. In a loose leaf securing system, the combination of a base frame having two pairs of relatively movable abutment plates, means for actuating said plates, said means including a spindle with radiating rods to each movable plate, said spindle being rotatable to an extent adapted to place said links beyond a dead center position relative to the spindle.

14. In a loose leaf securing system, the combination of a base frame having two pairs of relatively movable abutment plates reciprocably mounted in directions substantially at right angles to each other, thereby to release a leaf-binding and leaf anchoring mechanism, and means for actuating said abutment plates.

15. In a loose leaf securing system, the combination of a base frame having two pairs of relatively movable abutment plates reciprocably mounted in directions substantially at right angles to each other, thereby to release a leaf-binding and leaf anchoring mechanism, and a single means for actuating all of said movable abutment plates.

16. In a loose leaf securing system, the combination of a base frame having two pairs of movable abutments plates both plates of both pairs being reciprocably mounted in directions substantially at right angles to each other, thereby to release a leaf securing apparatus, and means for actuating both abutments of each pair.

17. In a loose leaf securing system, the combination of a base frame having two pairs of movable abutment plates both plates of both pairs being reciprocably mounted in directions substantially at right angles to each other, thereby to release a leaf-securing apparatus, and a single means for actuating both abutments of each pair simultaneously.

In testimony whereof I affix my signature.

RICHARD F. POWER.
